[57] CLAIM

The ornamental design for a bottle, as shown and described.

DESCRIPTION

FIG. 1 is a front perspective view of a bottle showing my new design with a closure being shown in broken lines for illustrative purposes only;

FIG. 2 is a side elevational view on a reduced scale, the opposite side being a mirror image thereof;

FIG. 3 is a front elevational view; and

FIG. 4 is a top plan view.

The rear is plain and unornamented.

FIG. 1

FIG. 2

FIG. 4

FIG. 3
